(57) **CLAIM**

I claim the ornamental design for the beverage cap assembly, as shown and described.

DESCRIPTION

FIG. 1 is a front elevation of a beverage cap assembly showing my new design;

FIG. 2 is a top plan view of a beverage cap assembly shown in FIG. 1;

FIG. 3 is an exploded side elevation of an over-cap that can be snap-fitted over the integral spout; and,

FIG. 4 is a top plan view of an integral spout of the design of FIG. 1 taken along line 3—3 of FIG. 3.

1 Claim, 4 Drawing Sheets

FIG. 1

FIG. 2

FIG. 4
